The ornamental design for an antenna, as shown and described.

DESCRIPTION

FIG. 1 is a top plan view of an antenna, showing our new design;

FIG. 2 is a front elevation view thereof;

FIG. 3 is a rear elevation view thereof;

FIG. 4 is side elevation view thereof;

FIG. 5 is a side elevation view thereof;

FIG. 6 is a top perspective view thereof;

FIG. 6A is an enlarged view of circle 6A of FIG. 6; and,

FIG. 6B is an enlarged view of circle 6B of FIG. 6.

The broken line in the figure drawings represents unclaimed environment only and forms no part of the claimed design.
